P. B. CAMP

WINDING MECHANISM

Filed April 24, 1924

UNITED STATES PATENT OFFICE.

PERCY B. CAMP, OF MAYWOOD, ILLINOIS, ASSIGNOR TO UNIVERSAL DRAFT GEAR ATTACHMENT COMPANY, A CORPORATION OF ILLINOIS.

WINDING MECHANISM.

Application filed April 24, 1924. Serial No. 708,643.

To all whom it may concern:

Be it known that I, PERCY B. CAMP, a citizen of the United States, and resident of Maywood, county of Cook, and State of Illinois, have invented certain new and useful Improvements in Winding Mechanism, of which the following is a specification, and which are illustrated in the accompanying drawings, forming a part thereof.

10 This invention relates to winding mechanisms particularly adapted for hand brakes on railway cars, and has for its objects to balance the stresses in the shaft when the winding power is being applied to the hand lever; to improve the means for releasing the winding mechanism; and to provide a hand grip in advantageous relationship to the hand lever to which the winding power is applied. Further objects contributing to 15 the improvement of winding mechanisms will become apparent as the disclosure proceeds and the description is read in connection with the accompanying drawings illustrating a selected embodiment of the invention, and in which—

Fig. 1 is a plan view showing the hand lever in winding position and indicating in dotted lines the scope of its movement in winding the shaft;

30 Fig. 2 is a side elevation corresponding to Fig. 1, with the lever cut away on the line 2—2 of Fig. 1;

Fig. 3 is a sectional view taken on the line 3—3 of Fig. 2;

35 Fig. 4 is a vertical sectional view taken on the line 4—4 of Fig. 3;

Fig. 5 is a sectional view taken on the line 5—5 of Fig. 4, looking upwardly at the face of the ratchet wheel, and

40 Fig. 6 is a section through the hand lever taken on the line 6—6 of Fig. 4.

A fragment of a car end is shown at 10 equipped with a bracket 11 having a laterally projecting arm 12 (Fig. 3) equipped 45 with a bearing 13 in which the upper end of brake staff, or other shaft, 14, is journaled, the lower end of the staff being reduced and journaled in a bracket 15 carried by the car frame.

50 The upper end of the staff is polygonal in cross section, as indicated at 16 in Fig. 1, and receives a ratchet wheel 17 having a complementary passage in its hub 18. A pin or rivet 19 passes through the hub and

the shaft to prevent longitudinal movement 55 and a flange 20 on the upper end of the hub serves as a guard to prevent the pin from injuring the operator when the brake staff is released after the brakes have been set.

60 The ratchet wheel is equipped onto the lower surface with teeth 21 arranged in continuous series and at its outer edge there is an annular lip 22 encircling the teeth and forming a shroud to protect them from dirt and ice and to protect the operator from the teeth.

65 The ratchet wheel is operated by a hand lever 23 arranged to swing between a position at an angle to the shaft, as illustrated in Fig. 1, and in the dotted lines in Fig. 4, and an inoperative position extending along the shaft, as shown in solid lines in Fig. 4. The lever is bent at 24 and divided into two forks 25 and 26, which straddle the shaft 70 and are fulcrumed on a pin 46 carried by a boss 27 on a fulcrum sleeve 28 journaled on the shaft 14 and supported against longitudinal movement by a collar 29, secured 75 to the shaft by a pin 30.

80 Adjacent to the bend 24 the lever is perforated and equipped with a pawl pivoted therein on trunnions 31 with one end 32 in position to cooperate with the teeth 21 and the other end 33 weighted to urge the end 32 into such engagement when the hand lever is raised to winding position. The construction and arrangement of the lever just described causes the pawl to be brought 85 into proper cooperative relationship with the ratchet by merely raising the lever to the dotted line position in Fig. 4.

80 The bracket 11 has a second arm 34 substantially parallel to the arm 12, and a pawl 35 is pivoted between them to engage 90 with the teeth 21 and prevent unwinding of the staff as the hand lever is moved from the position A in Fig. 1 towards a position B, or when the hand lever is dropped to inoperative position. This pawl takes the 95 form of a bell crank having one arm 36 for engagement with the ratchet teeth 21 and another arm 37 adapted to be acted upon by a cam or extension 38 on the fork 25 of the hand lever (see Fig. 4). The arm 37 has a finger 39 projecting laterally from one side to extend the area over which the pawl may be acted upon by the hand lever. 100 105

If the brakes are to be left applied the hand lever is moved to a position approximating that shown at A in Fig. 1, and dropped, or lowered, and in this position the cam 38 will not engage the arm 37 and the pawl 35 will continue to hold the staff against unwinding, or in other words, to hold the brakes applied. When the brakes are to be released, the hand lever is moved to a position approximating that shown at B in Fig. 1 and dropped, and the cam 38 will strike the arm 37 and free the arm 36 from the ratchet teeth. The possibilities of these operations is readily seen in Fig. 3.

In order to prevent the hand lever from rotating about the shaft and allowing the cam 38 to slide off the arm 37 without releasing the pawl, means are provided to limit the rotation of the shaft in both directions when the cam and pawl have once been engaged. The arm 12 extends down into the path of a lug 40 on the fulcrum 28 and limits the rotation in a counter clockwise direction on Fig. 1, and a flange, or rib, 41 on the arm 37 forms a guide for the side of the cam 38 and prevents rotation in the opposite direction.

The latitude allowed by these limits is sufficient to enable the operator to readily place the lever in position to trip the pawl 35 when that is desired and the arm 37, together with the finger 39, cover an area of corresponding latitude.

The lug 40 and the arm 12 also serve to limit the back movement of the hand lever corresponding to position B in Fig. 1.

The end of the hand lever is formed into a loop 42 to provide a secure grip for the operator. The bracket 11 is extended downwardly, as indicated at 43 in Fig. 2, and provided with a hand grip 44 on the left side of the shaft in convenient position for the operator's left hand. By this means the operator may stand on the step, grasp the grip 44 with the left hand and the loop 42 with the right hand, and operate the brakes with a feeling of security, and in a position that will enable him to use his weight and strength to the best advantage.

The ratchet wheel 17 will protect the teeth and the pawls from falling material and from the accumulation of ice in cold weather, thus preserving them in operative condition at all times. However, when anything goes wrong with the mechanism below the ratchet wheel the absence of any enclosing casing makes the parts readily accessible for examination, cleaning and repair. This is a very important advantage over winding mechanisms in which the teeth are subject to clogging by dirt or ice, and in which a casing serves both to hamper inspection and repair, and to collect dirt and water.

The angle or curve in the lever 24 permits it to lie close to the shaft in folded po-

sition and enables it to bring the pawl 32 into proper relation to the ratchet wheel when raised to winding position. It also permits the cam 38 to take a convenient relation to the arm 37, allowing the latter to freely engage the ratchet during the winding operation and thereafter to be engaged by the cam and swung to release the arm 36 from the teeth 21.

By placing the bearing 13 between the fulcrum sleeve 28 and the ratchet, the forces developed when power is applied to the hand lever are balanced and the lever and shaft turn about their axes in the bearing without any binding or distortion.

I claim as my invention:

1. A device of the class described, the combination of a shaft, a ratchet wheel secured thereto and having teeth on its lower side, a bearing for the shaft below the ratchet wheel, a sleeve journaled on the shaft below the bearing, a hand lever pivoted to the sleeve to swing between a winding position, at an angle to the shaft, and in an inoperative position extending along the shaft, and a pawl carried by the lever for engagement with the ratchet wheel when the lever is in winding position.

2. In a device of the class described, the combination of a shaft, a ratchet wheel in driving relation to the shaft, a hand lever adapted to be raised to a winding position for driving the shaft and to drop by gravity to an inoperative position out of the way, a pawl for engagement with the ratchet wheel to prevent unwinding of the shaft, an arm on the hand lever adapted to move the pawl to release the ratchet wheel, and means to hold the pawl and arm in engagement.

3. In a device of the class described, the combination of a shaft, a ratchet wheel in driving relation with the shaft, a hand lever universally mounted with respect to the shaft and adapted to be raised to a winding position and to drop by gravity to an inoperative position, means to effect a driving engagement with the shaft when the hand lever is raised, a pawl cooperating with the ratchet wheel to prevent unwinding of the shaft, an arm on the hand lever for releasing the pawl and a flange on the pawl to hold the lever in engagement therewith.

4. In a device of the class described, the combination of a shaft, a ratchet wheel on the shaft, a fulcrum member journaled on the shaft below the ratchet wheel, a hand lever pivoted to the fulcrum member to swing between a winding position at an angle to the shaft, and an inoperative position extending along the shaft, a pawl for effecting a driving engagement between the lever and the shaft when the former is in winding position and a bracket for support-

ing the shaft having a bearing interposed between the ratchet wheel and the fulcrum member.

5. In a device of the class described, the combination of a car end, an upright shaft, a ratchet wheel in driving engagement with the shaft, a bearing beneath the ratchet wheel in which the shaft is journaled, a bracket on the car end having an arm carrying said bearing, a pawl mounted on the arm and engaging the ratchet to prevent unwinding, a hand lever universally mounted on the shaft below the bearing, means for effecting a driving engagement between the ratchet wheel and the hand lever when the lever is raised, and means for releasing the pawl from the ratchet wheel when the lever is lowered.

6. In a device of the class described, the combination of a car end, an upright shaft

adjacent to the car end, means for rotating the shaft including a hand lever pivoted to swing between a winding position at an angle to the shaft, and an inoperative position extending along the shaft, a bracket 25 carried by the car end and having a bearing for the shaft and a hand grip carried by the bracket at one side of the shaft.

7. In a device of the class described, the combination of a car end, a bracket on the 30 car end having a bearing therein, an upright shaft journaled in the bearing, means for rotating the shaft including a hand lever pivoted to swing between a winding position at an angle to the shaft and an inoperative position extending along the shaft, and a hand grip on the bracket at the left side of the shaft.

PERCY B. CAMP.
